CLAIM

The ornamental design for pair of blade holders for a mat-cutter side block, as shown and described.

DESCRIPTION

FIG. 1 is a perspective view of the pair of blade holders for a mat-cutter side block showing my new design; FIG. 2 is a top plan view of the pair of blade holders for a mat-cutter side block showing the foremost blade holder of my new design, the other being omitted for illustrative purposes only;

FIG. 3 is a front elevational view thereof;

FIG. 4 is a right end elevational view thereof;

FIG. 5 is a rear elevational view thereof;

FIG. 6 is a left end elevational view thereof;

FIG. 7 is a bottom plan view thereof;

FIG. 8 is a top plan view of the pair of blade holders for a mat-cutter side block showing the rearmost blade holder of my design, the other being omitted for illustrative purposes only;

FIG. 9 is a front elevational view thereof;

FIG. 10 is a right end elevational view thereof;

FIG. 11 is a left end elevational view thereof;

FIG. 12 is a rear elevational view thereof; and

FIG. 13 is a bottom plan view thereof.

The broken line showing the side block is for illustrative purposes only and forms no part of the claimed design.
